SLEEPING CAR

David F. Zook, Evanston, Ill.

Application August 12, 1935, Serial No. 35,841

1 Claim. (Cl. 105—315)

The invention relates generally to sleeping cars, and more particularly to cars of the corridor type which are adapted for convertible use so as to provide sleeping facilities during the night and seating facilities during the day.

An important object of the present invention is to provide a corridor type sleeping car of standard size and dimensions embodying a novel and advantageous construction of the sleeping and seating facilities whereby the available space is utilized with such a degree of efficiency as to furnish seating and bed facilities for at least the same number of passengers as are accommodated in a standard Pullman car, and so arranged that all of the beds are located at a convenient and readily accessible height above the adjacent floor level, thereby eliminating the unpopular and inconvenient upper berths of present day equipment.

More specifically, it is an object of the invention to provide such a corridor type sleeping car embodying a series of rooms arranged at different levels in the car, with each of such rooms having both sleeping and seating facilities, and being accessible directly from the corridor without inconvenience to the passengers in the other rooms. By reason of this "two-level" arrangement of the car, and the accessibility of all of the rooms from a common corridor, I choose to call the car a "mezzanine-type of corridor sleeping car".

Another object is to provide a sleeping car of this type wherein complete privacy is afforded the occupants of any particular room independently of and without inconvenience to the passengers in other rooms.

Another object is to provide a car of this type so constructed that each room has lounging facilities for its passengers.

A further object is to provide a corridor type car arranged to provide unusual visibility on both sides of the car for the passengers in all of its rooms, and embodying unusual convertibility so as to meet the demands of large parties by permitting inter-communication of a number of its rooms or sections during day or night use.

Another object is to provide a mezzanine car of the corridor type having a passenger capacity at least equal to that of a standard Pullman car and embodying longer and wider beds, greater and more readily accessible luggage space, greater toilet facilities, individual wash basins for each bed, and having ample headroom for the passengers when dressing or disrobing.

Other objects and advantages will become apparent from the following description, taken in

connection with the accompanying drawings, in which:

Fig. 1 is a vertical longitudinal sectional view illustrating the central portion of a car embodying the features of the invention, the view being taken substantially along the line 1—1 of Fig. 3, in the direction indicated by the arrows, and omitting certain of the doors and wash basins for the sake of clarity of disclosure.

Fig. 2 is a fragmental plan sectional view of the car taken substantially along the line 2—2 of Fig. 3.

Fig. 3 is a vertical sectional view of the car taken substantially along the line 3—3 of Fig. 1, looking in the direction shown by the arrows.

Fig. 4 is a vertical cross sectional view similar to Fig. 3, but showing the adaptation of the invention to a car of standard sleeping car dimensions and proportions, as contrasted with the straight side wall construction and relatively low floor level of the form shown in the other views, this view being taken along the line 4—4 of Fig. 1.

Fig. 5 is a horizontal sectional view showing the women's end of the car, the view being taken along the line 5—5 of Fig. 7.

Fig. 6 is a similar horizontal sectional view taken along the line 6—6 of Fig. 8, and showing the men's end of the car.

Fig. 7 is a vertical sectional view taken along the broken line 7—7 of Fig. 5.

Fig. 8 is a vertical sectional view taken along the line 8—8 of Fig. 6.

Fig. 9 is a plan view of the locker space in the women's end of the car, the view being taken in section along the line 9—9 of Fig. 7.

Fig. 10 is a similar plan section of the locker space at the other end of the car, the view being taken along the line 10—10 of Fig. 8.

Fig. 11 is a plan section taken along the line 11—11 of Fig. 1, and showing one arrangement of two adjoining lower level rooms.

Fig. 12 is a view similar to Fig. 11 and showing a different arrangement of the same two rooms.

Fig. 13 is a detail view illustrating a locking device employed for holding the roll-beds of the lower rooms in any desired position.

Fig. 14 is a cross sectional view of one of the roll-beds employed in the lower rooms of the car.

While I have shown in the drawings and will herein describe in detail the preferred embodiment of my invention, together with one alternative embodiment thereof, it is to be understood that I do not thereby intend to limit the inventions to the specific forms disclosed, but aim to cover all modifications falling within the spirit

15

20

25

30

35

40

45

50

55

and scope of the invention as expressed in the appended claims.

In the form chosen for illustration herein the invention is embodied in a car having side walls 15 and 16, a roof 17 and a floor 18 carried by trucks 19 in a conventional manner. In accordance with the present invention, the car and trucks may be of a standard form and dimensions as illustrated in Fig. 4, with a relatively high floor level as measured above the rails and with inwardly stepped side walls, or the car may have the straight sides, a rounded top and a lower floor level as shown in Fig. 3 and the other figures of the drawings.

15 By means of a longitudinally extending partition 20 located adjacent to the side wall 15, the car is divided to form a corridor 21, extending along one side of the car throughout substantially the entire length thereof, and providing 20 convenient access to a series of similar two-level room-units 22 located between the partition 20 and the other side wall 16 of the car. Room-units 22 of similar size and construction are employed throughout the major portion of the car 25 length, the proportioning being such that there is provided (as shown in Figs. 5 to 8) a ladies' toilet section 23 and a combined porter's bunk and men's toilet section 24 located at opposite ends of the car. The section 23, as indicated by 30 a bracket and a reference numeral in Fig. 5, also includes a vestibule 30, and defines a length of locker space at the women's end of the car. At the other end of the car, the bracket and the reference numeral 24 include a vestibule 95, and 35 show a length of locker space available with the present arrangement. In the end sections 23 and 24 of the car the corridor 21 is offset as at 21' and 21" to meet the centrally located vestibule doors 25.

40 The room-units 22 are normally defined and separated from each other by transverse partitions 26, and as best illustrated in Fig. 1, each unit comprises two lower or main floor rooms 27 and an elevated yet readily accessible mezzanine room 28. Generally considered, the elevated or mezzanine room 28 of each room-unit is T-shaped in longitudinal section, the vertical or central portion of the T extending downwardly between the two lower rooms 27 of the unit and 45 having an entryway 29 at one end (Fig. 2) through the partition 20 into the corridor 21. The laterally extending portions of the T are defined at their ends by the upper portions of the walls 26, and on their lower sides by a floor 30, 50 and this space is utilized to form two permanent beds or berths 31 (Fig. 2) which extend transversely of the car. As shown in Figs. 1, 2, and 3, the seating facilities in the mezzanine rooms 28 are provided by two permanent upholstered corner seats 32 located in the downwardly extending portion of the room in the corners formed by the side wall 16 and front and rear partition walls 33, which walls 33, with a floor 34, define said downwardly extending portion of the room. 55

60 Drop seats 35 are also provided on each of the partitions 33. These drop seats preferably terminate short of the corridor partition 20, as illustrated in Figs. 2 and 3, thereby providing space, on opposite sides of entryway 29 for full opening 65 of doors 46. In the corners defined by partition 20 and the walls 33, on opposite sides of the entryway 29, a pair of wash basins 36 are mounted in fixed position. Piping 36' serving the basins 36 passes out through partition 20 at about the mezzanine floor level, as shown at 36", and is 70

located on the corridor side of the partition 20 from that point to the floor of the car. This construction is employed in order that the piping 36' may not interfere with the free rolling of beds 50 which are provided in the main floor rooms. 5 On the corridor side, this piping 36' is enclosed by a light, removable shield 20A as shown in Figs. 5 to 8.

In the form illustrated in Fig. 4, the corner seats 32 are eliminated, and the wash basins 36A 10 are mounted on vertical bearings in corresponding corners adjacent to the side wall 16 of the car, and the basins may be pivoted to out-of-the-way positions under the recessed roof of the car as shown. 15

It will be noted that mezzanine rooms 28 provide duplicate and independent washing, seating and sleeping facilities along their front and rear sides so that by providing independent lights 37, a pair of clothes hooks 38' on each side of wall 20 26, and hooks 38 for supporting curtain 39, the room is fitted for use as two semi-private sections for occupancy by separate parties of one or two persons each. These rooms, with their permanent berths 31, provide unusually convenient lounging facilities for day-time travel, and are rendered safe for sleeping by nets 40 which may be stretched along the edges of the berths between hooks 41.

In the proportioning of parts herein illustrated, 30 the floor 30 of the berth portions is slightly lower than the ceiling 42 of the corridor 21, and one end portion of the mattress 43 of the berth rests directly on the upper surface of the ceiling 42. Throughout the balance of the length of the 35 mattress 43 it is carried on springs 44 resting on the floor 30.

In view of the transverse positioning of the berths 31, the mattress 43 may be made of ample length, and by locating the same equally spaced 40 from the side walls 15 and 16, convenient storage space is provided at opposite ends of the mattress to receive suit cases and the like. During day travel such suit cases may, if desired, be transferred to positions on the mattress 43 so as to 45 permit light to enter freely through windows W-3 which are located in the walls 15 and 16 at opposite ends of each berth 31. Additional window W-4 is provided in each room 28 in the wall 16 between seats 32, this window being of a 50 greater height than windows W-3.

Opposite the windows W-4, windows W-5 and W-6 are provided in the wall 15, windows W-5 opening into the corridor opposite the entryways 29, while windows W-6 are of a size corresponding to windows W-3 and open into the mezzanine rooms over the entryways 29. Preferably additional windows W-5 are also provided in the side wall so that there are three such windows in the corridor 21 opposite each 60 room-unit 22 as indicated in Fig. 5.

As hereinbefore mentioned, the access to the mezzanine rooms 28 is convenient, and is provided by steps 45 in the entryway 29, the lower step extending slightly into the corridor 21 as 65 illustrated in Fig. 2. In the entryway 29, inwardly swinging doors 46 are provided which are mounted at an angle as shown in Fig. 3 on narrow transverse partitions 29a which flank the entryway 29 on its opposite sides. In the form 70 shown in Fig. 4, the doors 46a are mounted vertically for outward swinging movement. To provide headroom over the steps 45, the corridor ceiling 42 may be cut away to form an opening 47 (Fig. 2) which opening may be closed by 75

flap-like doors 48 as shown in Fig. 4, or by a curtain or rolled shade 49 as shown in Figs. 2 and 3.

As illustrated in Figs. 1 and 4, the seating and sleeping facilities for the lower rooms 27 are provided by roll-type beds 50, extending transversely of the car, and which for day use as seats, are rolled back against partition 51 into the space beneath the floor 34 of the mezzanine room of the same room-unit. In this position the rear edge of the bed is in substantial abutment with partition 51 which separates the two rooms 27 of the unit, while the front edge of the bed 50 projects into the room, toward partition 26, and a sufficient distance beyond the partition 33 to form a seat of ample depth extending substantially the entire width of the room.

To provide a suitable back to cooperate with the extending portion of the bed 50 to form a seat, a permanently mounted head rest 53 is fixed on the lower portion of the face of partition 33, while a pair of removably mounted cushioned seat backs 54 are suspended from the lower edge of the partition 33 to extend down substantially to the upholstered upper surface of the bed 50. In the form shown, a horizontal shelf 55 extends from the wall 51 toward the normal location of seat backs 54 to engage the seat backs and maintain the same in the desired angular position. By locating this shelf in spaced relation to the floor 34 of the superposed room 28, and in spaced relation to the top of the bed 50, a convenient and readily accessible storage space 56 is provided for the room 27. Thus the spaces beneath the floor 34, defined by the floors 18 and 34 and the wall 51, and provided with luggage shelf 55, may be termed a luggage and bed alcove, which extends transversely of the car for the full width of the room. The top of the concealed portion of the bed, beneath the shelf 55, may also serve as storage space during the day.

As shown in Figs. 1, 4, and 14, the beds 50 are formed with box-like bases 57 having rollers 58 running in shallow grooves or tracks 59 in the floor 18 of the car to facilitate shifting between day and night positions. Preferably each bed is formed in two longitudinally extending sections as shown in Fig. 14 so as to facilitate installation and removal of the beds, the two sections being bolted together as at 60. An upstanding marginal rim 61 on the base 57 retains the seat cushion 62 in position on the bed, and at the rear of the bed the rim 61' is somewhat higher to prevent mattress 63 from sliding off the bed. For night use, the mattress 63, which is formed in two parts, is removed from the storage space within the bed base 57 (Fig. 1, right hand room) and is placed upon the seat cushion 62. At the same time, the removed seat backs 54 may be stowed within the base 57.

Preferably each bed is provided with a locking device such as that illustrated in Figs. 13 and 14. This device in the form shown comprises a pair of rubber bumpers 64 mounted with in the base 57 for projecting movement through the ends thereof into contact with partition 20 and side wall 16. Springs 65 normally retract the bumpers 64, while a cam 66 on the rear end of a rod 66', which is connected to and operated by a lever 67 at the front edge of the bed, may be actuated to urge the bumpers outwardly to their active clamping positions. Thus the bed may be rolled out to any desired extent during the day so as to meet the requirements or desires

of the individual passenger, and it may be securely locked in the desired position.

For each room 27 a window W-7 is provided in the wall 16; an individual light 68 is provided, and an individual wash basin 69 is mounted in each room 27 in the corner formed by walls 16 and 26. An individual entry is provided for each room 27 by a door 70, which door may be of the sliding type as in Figs. 6, 8, 11, and 12, or of the inwardly swinging type as shown in Figs. 5 and 7. When the swinging type is used, the door may be of two sections, as illustrated in Fig. 7, to permit swinging of the upper section thereof inwardly over the bed after it has been shifted to its outer or sleeping position. In each instance a glass panel 71 is mounted in the door, and a window 72 is provided in the partition 20 beside the door and opening into the room 27. In the preparation of the room for sleeping, the bed may be partially withdrawn, or may be moved back and forth as required for convenient performance of the necessary operations. After being completely made up, the bed may be returned to its out-of-the-way position for the convenience of the passenger. The passenger, upon retiring, may rest upon the bed, and by pressing against the head rest 53, roll the bed to its outermost position where it may be fixed by operation of the locking lever.

As illustrated in Figs. 11 and 12, the partition 26 between the mezzanine floor 30 and the car floor 18 is formed in four sections, one section 26a between the wash basins 69 being stationary, while three sections 26b are hinged together and are removably mounted. Thus the three sections 26b may be removed, together with a removable end post 26c, so that the two adjoining rooms 27 of the adjoining units 22 are thrown together into a commodious space free from all obstructions. Further freedom and visibility on both sides of the car is provided by fastening the two doors 70 in their open positions as shown in Fig. 11.

For further convenience and adaptability, the upper or mezzanine rooms 28 are also constructed to permit inter-communication in the event that large parties are to be accommodated. To this end each wall 26, in the upper stationary part between rooms 28, has an upwardly swingable door 30a therein, which door or panel may be shifted or pivoted upwardly to and fixed in the horizontal position shown in dotted outline in Fig. 1. It should be noted that the convenience of intercommunication of the several rooms of the upper tier may be obtained in either day or night use of the car. Also the adjacent rooms of the lower tier are similarly adaptable.

As an added feature of utility, the present car is particularly convenient for the transportation of invalids and the like, since a window W-5 in the wall is positioned opposite the door of each lower room of the car. These windows W-5 are preferably constructed for convenient removal so that a stretcher may be moved into any lower room by removal of the opposite window W-5.

The ladies' end of the car as illustrated in Figs. 5 and 7 is formed by a jogged partition 75 which defines the offset portion 21' of the corridor 21. In one portion of the wall 75 which constitutes a continuation of the partition 20, an entry door 76 is provided and by suitable partitions and doors, two compartments 77 are formed along wall 16 for each of the toilets 78. Individual windows W-8 are provided in the wall 16 for the compartments 77. Outside the compart-

ments 77, but inside of the section, and against the wall 26 of the adjacent room 27, a wash basin 79 is mounted.

The extent of end section 23 of the car is indicated in Fig. 5 by the bracket 23 and includes the women's toilet room and the adjacent vestibule 80, and defines a length of locker space at that end of the car. The corridor ceiling 42 terminates at 14 (Fig. 5) and from that point to the car end wall 13, the corridor portions 21 and 21' extend the full height of the car. A false roof 30' covers the entire ladies' toilet space, and is on the same level as the mezzanine floor 30, and forms the floor for lockers L-2 and L-3.

In the present instance locker L-2 is utilized to house an air conditioning unit 83 of conventional construction. This locker is provided with doors 82, which allow of inspection and ordinary servicing of the unit 83. For complete accessibility the sectional insulated wall 82' is removable, as is also a lighter partition 13', adjacent the vestibule space, while a removable cover-plate 83' on the car wall 16 permits of easy installation or removal of unit 83.

By means of a horizontally extending duct 84 in the wall 16 between the bottoms of windows W-4 and the tops of windows W-7, conditioned air from the unit 83 is discharged through ports 85 into each lower room 27. A similar duct 86 located immediately above the corridor ceiling 42 (Fig. 3) serves to supply conditioned air to each of the mezzanine rooms 28 through ports 86'.

Locker L-3 is a very large, undivided space, closed by doors 87, and provides storage space for unwieldy and bulky articles. In the vestibule 80, false roofs 30' are also provided over the car steps and this permits lockers L-4 to be built in this space, which lockers are served by doors 81.

At the other or men's end of the car (Figs. 6, 8, and 10) the bracket 24 includes the men's toilet room, porter's bunk, and adjacent vestibule 95, and within this length of the car, a large amount of locker space is provided. The corridor offset 21' occurs at the partition 26 of the end room 27, a porter's bunk compartment being located along the wall 15 in alignment with the corridor 21, while a wall 89 defines a men's toilet room 90 along wall 16. The room 90 has two communicating compartments with individual windows W-8, the compartment adjacent to the end of the car having a toilet 91 therein, while the other compartment is accessible from the corridor 21' and has a urinal 92 and a wash basin 93 located therein.

The porter's bunk compartment is provided with an upholstered seat 94 located against the wall 11 of the vestibule and facing toward the other end of the car. At the other end of the compartment 88 and spaced from the seat 94 is an upholstered bench 96 of the same height as the seat 94, and a shiftable cushion 97 which normally forms a back for the seat 94 may be positioned between the seat 94 and the bench 96 to form a full length bunk for the porter. Over the bench 96, the end of the compartment 88 is preferably formed by a glass display cabinet 98 for the display of articles ordinarily sold by the porter. Beneath the cabinet and above the bench 96 is an open space 99, and through this space and the glass display cabinet the porter may have a clear view of the corridor at all times.

The end 24 of the car, as defined by the bracket in Fig. 6, also provides abundant locker space, the floor 30' of these lockers constituting a false roof or ceiling over the men's toilet compart-

ments and over the porter's bunk, and also extended into the vestibule space 95 as at 30' for the provision of two lockers L-1 over the car steps as at the other end of the car.

The corridor ceiling terminates at 12 (Fig. 6) and from the partition 26 to the car end wall 11, the corridor 21' extends up the full height of the car. The locker doors thus swing into this full-height corridor space. Over the toilet compartments 90, lockers L-7 and L-4 are provided. Between the end of the porter's bunk and the partition 26 of the end room 27, a locker L-8 is formed, while directly over the compartment 88 is a long shallow locker L-5 adapted particularly for storage of the hinged removable sections of the partitions 26. The locker L-5 as herein shown has a single horizontally hinged door 100 as distinguished from vertically hinged doors 101 which are provided for the relatively large locker L-6 above the locker L-5. Similar vertically hinged doors are, of course used on the other lockers. In the corner of the corridor formed by the end wall 26 and the wall 89 of the men's room, a triangular locker 102 is preferably provided for containing a switch panel, a water cooler, or other desired equipment. The corridor 21 is provided with lights 103 (Figs. 3, 4, 5, and 6) installed in the corridor ceiling as indicated opposite each mezzanine entryway, for correct illumination at night.

From the foregoing description it will be evident that the present invention provides a car wherein a novel and advantageous disposition and construction of sleeping and seating facilities makes it possible to afford greater comfort, convenience and privacy to all of the passengers. The arrangement is such that all of the beds are wider and longer than in the conventional Pullman, while the accessibility of the upper or mezzanine beds renders it feasible for two persons to occupy each mezzanine bed. When the car contains five room-units 22, there are twenty beds available, so that with the convenient double capacity of each mezzanine bed, the maximum passenger capacity is increased to forty persons.

Other features of the present car also mark an advance in efficiency by providing increased convenience and capacity of the storage room and baggage space, added visibility from all of the rooms on both sides of the car, greater toilet and washing facilities, and convenient convertibility of the various rooms to meet the demands and wishes of various groups of passengers.

I claim as my invention:

In a sleeping car of the side-aisle type, having passenger accommodations therein disposed upon two levels, said passenger accommodations being disposed between said aisle and the remote side wall and extending the greater part of the car length, service and storage facilities of full car height occupying a section of car length immediately adjacent to the two car end-walls and separating said end-walls from immediate contact with the passenger sleeping and seating portion of the car, said passenger accommodations comprising a plurality of similar room-units, each of said room-units consisting of two corridor level rooms with abutting bed alcoves, and a superimposed two-bed, two level mezzanine compartment, the lower rooms of abutting room-units constituting adjoining rooms, said adjoining rooms of abutting room-units being sepa- 75

5 rated by a transverse partition having a fixed section at the car-wall side, a wash basin in each of said adjoining rooms mounted in the corners formed by the car wall and the fixed section of said partition, the remaining section of said partition being a hinged removable portion and a removable end post at the corridor end of the partition, a window in the car side wall in each of said lower rooms, door openings from said lower rooms into said corridor, sliding doors for said openings which when closed abut said end

10 post, said doors when opened being moved back alongside of the corridor partition whereby removal of said transverse partition section throws the two adjoining lower rooms into a single compartment for day or night use, while further removal of said end post and opening of said sliding doors provide, for day use, a large unobstructed space including the adjacent corridor and extending the full width of the car.
